[57] **CLAIM**

The ornamental design for a pickup truck camper unit,
as shown and described.

DESCRIPTION

FIG. 1 is a perspective view of a pickup truck camper unit showing my new design, it being understood that the broken lines are for illustrative purposes only;

FIG. 2 is a side elevational view thereof, showing the side opposite to that shown in FIG. 1;

FIG. 3 is a front elevational view thereof; and

FIG. 4 is a rear elevational view thereof.

*Fig.1.**Fig.2.**Fig.3.**Fig.4.*
